Primary Examiner — Kevin K Rudzinski*Assistant Examiner* — Paul D Bohannon(74) *Attorney, Agent, or Firm* — Buche & Associates, P.C.; John K. Buche; Bryce A. Johnson**CLAIM**

The ornamental design for a grow light, as shown and described.

DESCRIPTION

FIG. 1 is a perspective view of a grow light; FIG. 2 is a bottom view of the grow light of FIG. 1; FIG. 3 is a top view of the grow light of FIG. 1; FIG. 4 is a right-side view of the grow light of FIG. 1; FIG. 5 is a left-side view of the grow light of FIG. 1; FIG. 6 is a front view of the grow light of FIG. 1; FIG. 7 is a back view of the grow light of FIG. 1; and, FIG. 8 is an environmental view of the grow light of FIG. 1. The nature and intended use of the article in which the design is embodied is a light for horticulture and other husbandry.

Broken lines illustrate environmental features and form no part of the claimed design.
